UNITED STATES PATENT OFFICE.

WILLARD I. TWOMBLY, OF NEW YORK, N. Y., ASSIGNOR, BY MESNE ASSIGNMENTS, TO THE WILCOLATER COMPANY, OF NEWARK, NEW JERSEY, A CORPORATION OF DELAWARE.

CONTROL MECHANISM.

Application filed June 6, 1922. Serial No. 566,424.

This invention relates to apparatus for controlling the supply of fuel to fuel-consuming devices, and more specifically has to do with control mechanism by which the flow of fuel to burners may be controlled so that a relatively constant predetermined temperature may be maintained in a chamber heated by the burners for a predetermined length of time. This mechanism is particularly adapted for use in connection with gas stoves having an oven chamber. Heating devices of this kind have heretofore been provided with regulators which operate to control the flow of fuel so that a constant temperature in a chamber is maintained throughout a given period of time, but these regulators have not been designed primarily for the purpose of producing a compact, easily operated, enclosed device. The clock mechanism by which the flow of fuel is controlled for a given period of time is located at one point in the fuel line, while the temperature control may be located at another. Devices of this sort are consequently not suitable for use in gas stoves where convenience of operation is of great importance and where economy of space must also be emphasized.

The present invention is directed to the provision of a device which is compact and occupies little space, and which is also readily operated, with the elements by which the device is set placed conveniently for the operator. The device includes a pair of casings, separated by a common partition wall in which is a passage provided with a valve. This valve is normally biased toward the closed position, and a clock mechanism is mounted in one of the casings and arranged so that when the valve has been manually set in open position it is locked there by suitable means which are released by the clock mechanism after a predetermined lapse of time. The gas flows into the casing which contains the clock mechanism, passes through the valve when the latter is open, into the second casing in which is a thermostatic control device, including a valve through which the gas flows to an outlet to the burner. This control device includes an element which is responsive to temperature changes and is placed in the chamber heated by the burner. The gas flowing from the first casing into the second,

flows out through the burner under the control of the thermosytatically operated valve. The clock mechanism is set by a lever placed on the first casing, and a setting device for the thermostatic mechanism is placed on the second casing, so that the two setting devices may be conveniently manipulated.

In the accompanying drawings there is shown one form of the invention which is found to be satisfactory, and in these drawings Fig. 1 is a view showing in side elevation one form of apparatus embodying my invention. Fig. 2 is a horizontal sectional view on the line 2-2 of Fig. 1, and Fig. 3 is a vertical sectional view on the line 3-3 of Fig. 2.

Similar reference characters refer to similar parts in each of the several views.

Referring first to Figs. 1, 2 and 3, the reference character F designates a casing apertured at one end to receive a pipe 12, which may be connected with a source of gas or other fuel. The opposite end of the casing F constitutes a wall 10, provided with a port 11, in which is interposed a manually operable valve D. This valve is biased to the closed position by a spring 38, one end of which is anchored to the casing F, and the other end of which is attached to the stem of the valve D. This valve is provided with a handle 39, by which it may be opened manually in opposition to the force exerted by the spring 38.

In order to lock the valve D in the open position I provide the stem of this valve with a hole or recess 14, and I also provide a pin 15 which may be moved into and out of the recess 14. The hole 14 and the pin 15 are so located that when the valve D is open the pin may be projected into the hole to keep the valve open; obviously when the pin is subsequently withdrawn from the hole in the valve stem the valve will close under the influence of the spring 38.

The pin 15 is pivotally attached to a plate 16 which is mounted to rock on a stud 17 fixed in a bracket 19, which latter is attached to a plate 23 mounted in the casing F. The stud 17 carries a spring 18, one end of which is fixed to the stud and the other end of which bears against the rocker plate 16, the effect of this spring being to bias the plate 16 in such direction as to project the pin 15 into the hole 14 in the stem of valve

D. The plate 16 may be rocked in the other direction by a nut 40 which travels on the threaded end 21 of a shaft 20. That is to say, the left hand end of the plate 16 as viewed in Fig. 2 is apertured to surround the flanged nut 40, so that when the shaft 20 is turned in such direction as to draw the nut inwardly, the plate 16 is rocked in opposition to the spring 18 and thereby 10 operated to withdraw the pin 15 from the hole 14.

The shaft 20 is journaled in the plate 23, and also in the front wall of the casing F, and the shaft projects through the front 15 wall of the casing to receive a key 22 by which the shaft may be turned by hand.

Associated with the shaft 20 is a clock work mechanism H comprising a main spring 24, one end of which is attached to 20 the plate 23, and the other end to the shaft itself, which spring tends to rotate the shaft in such direction as to draw the nut 40 inwardly to release the valve D. Such rotation of the shaft 20 is restrained however, 25 by the remainder of the clock work mechanism H, comprising a gear 41 loosely mounted on the shaft 20 and carrying a spring-pressed pawl 41' engaging the teeth of a ratchet wheel 41^a secured to the shaft, 30 a train of gears 26 and 27, an escapement wheel 28, a pallet 42 and a hair spring 29. The operation of the parts thus far described is as follows:

In order to set the device for a given 35 interval of time the valve D is first opened by hand, and the key 22 is then turned to the proper point, thereby permitting the pin 15 to enter the hole 14. The valve D is then locked in the open position and the 40 clock work mechanism H immediately begins to turn the shaft 20 in such direction as to draw the nut 40 inwardly, thereby gradually withdrawing the pin 15 from its locking position. At the expiration of the given 45 interval of time this pin is fully withdrawn, whereupon the valve D closes under the influence of its controlling spring 38 and so the supply of gas is discontinued.

The front face of the casing F is provided with a dial 37, the circumference of 50 which is divided into 12 spaces each representing a time interval of 5 minutes, and a pointer 36 is attached to the shaft 20 and arranged to move over the dial. The clock 55 work mechanism H is so designed that a period of one hour will be required to move the pointer 36 around the entire circumference of the dial 37; in other words, one complete revolution of the shaft 20 consumes 60 one hour. Thus if, when the valve is locked in the open position in the manner which has been described, the key 22 and pointer 36 are moved counter-clockwise two full revolutions, the valve will open at the end of 65 two hours.

When the pointer 36 is opposite the "60" mark on the dial, the nut 40 is in such position that pin 15 is withdrawn from the hole 14. Upon turning the shaft 20 to the right, as viewed in Figure 1 the nut 40 will be 70 moved to lock the valve D and the angular displacement of the shaft as measured by the position of the pointer 36 on the dial 37 will be a measure of the time interval required to again release the valve D. Thus 75 the device can be set for any interval from 1 to 60 minutes, by any fraction of a complete rotation of the shaft 20, and it can be set for any number of hours by any corresponding number of complete rotations of 80 the shaft.

The port 11 in the casing F leads into a second casing E from which the gas is taken through a nipple 13 to the burner or other fuel consuming device. The path 85 through which the gas flows from the port 11 includes a chamber 30, a passageway 31, a valve 43 and a port 32 leading into the nipple 13. The valve 43 is controlled by a thermostat device designated as a whole by 90 the reference character G which device is disclosed and claimed in my Patent No. 1,616,419, granted Feb. 8, 1927, for controls for regulating temperature.

Briefly described, the device G comprises 95 a bellows 33 controlling the position of the valve 43, and which bellows in turn is controlled by the pressure of gas in a bulb 34, which is placed in the chamber to be heated. As explained in my patent referred to above, 100 the thermostatic device G may be adjusted to maintain any desired constant temperature within the oven or other chamber which is heated by the gas supplied from the nipple 13. The mechanism of the automatic temperature control forms no part of my present invention and so is not fully described.

It will be seen from the foregoing that by 110 virtue of the combined thermostat and time control I am enabled to maintain the temperature in the oven at any desired constant value for any desired interval of time.

Although I have stated that in the form 115 here shown the thermostatic device G is the same as that described and claimed in my patent above mentioned, it is understood that this particular thermostatic device may be replaced by any other form of thermostatic device such for example as that shown in my application filed on the 1st day of May 1922, Serial No. 557,669 for thermostatic controls, and that shown in my co-pending application filed on the 8th day of June 1921, Serial No. 476,025 for thermostatic controls for 120 gas ovens.

What I claim as my invention is:

1. In combination, a device biased to 125 closed position for admitting fuel to a fuel-consuming element, a threaded shaft rotatable freely in one direction and biased to 130

- rotate in the opposite direction, clockwork mechanism for restraining the rotation of said shaft in response to its biasing force, a traveller nut coacting with the threads on said shaft, and means controlled by the travel of said nut on its shaft for locking said device in open position. 2. In combination, a threaded shaft biased to rotate in one direction and rotatable freely in the opposite direction, clockwork mechanism for restraining rotation of said shaft in response to its bias, a traveller nut co-
- acting with the threads on said shaft, a device biased to the closed position for admitting fuel to a fuel-consuming element, a pin coacting with a recess in said device to lock the device in open position, means for biasing said pin to locking position in its recess, and a connection between said nut and said pin for withdrawing the pin as the nut travels along said shaft due to rotation of the shaft in response to its bias. 15 20

WILLARD I. TWOMBLY.
